(57) **CLAIM**

We claim the ornamental design for a packaging for food product, as shown and described.

DESCRIPTION

FIG. 1 is a top perspective view of a packaging for food product;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The dash-dash and dash-dot boundary line(s) defines the boundary of the claimed design and forms no part of the claimed design. The broken lines in the drawings form no part of the claimed design and are only for illustrative purposes, and/or to show environmental structure.
